DESIGN FOR A HANDBAG

Florence N. Lewis, New York, N. Y.

Application August 31, 1937, Serial No. 71,402

Term of patent 7 years

To all whom it may concern:

Be it known that I, Florence N. Lewis, a citizen of the United States, residing at New York, in the county of New York and State of New York, have invented a new, original, and ornamental Design for Handbag, of which the following is a specification, reference being had to the accompanying drawings, forming a part thereof, in which

I claim:

The ornamental design for a handbag as shown.

FLORENCE N. LEWIS.
